[57] CLAIM

The ornamental design for a surgical instrument holding tray, as shown and described.

DESCRIPTION

FIG. 1 is a front perspective view of a surgical instrument holding tray, showing our new design;
FIG. 2 is a top plan view thereof;
FIG. 3 is a side elevational view thereof, the opposite side elevational view being identical thereto;
FIG. 4 is a front elevational view thereof;
FIG. 5 is a rear elevational view thereof;
FIG. 6 is a bottom plan view thereof;
FIG. 7 is a cross-sectional view thereof, taken along line 7—7 of FIG. 2; and,
FIG. 8 is a cross-sectional view thereof, taken along the line 8—8 of FIG. 2.

*Fig. 1.**Fig. 7.**Fig. 8.**Fig. 3.*

Fig. 5.

Fig. 6.

UNITED STATES PATENT AND TRADEMARK OFFICE
CERTIFICATE OF CORRECTION

PATENT NO. : Des. 334,973

DATED : Apr. 20, 1993

INVENTOR(S) : A. H. Llynn Valentine, Rudy Gaba

It is certified that error appears in the above-identified patent and that said Letters Patent is hereby corrected as shown below:

Title page, item [73] Assignee, the address should read
"Chatsworth" and not -- Torrance--.

Signed and Sealed this
Fifth Day of April, 1994
